UNITED STATES PATENT OFFICE.

JOSHUA DAVIES, OF MUSKEGON, MICHIGAN.

DESIGN FOR HITCHING-POST.

Specification forming part of Design No. 7,802, dated October 13, 1874; application filed October 1, 1874.
 [Term of Patent 7 years.]

CASE D.

To all whom it may concern:

Be it known that I, JOSHUA DAVIES, of Muskegon, in the county of Muskegon and State of Michigan, have invented a Design for a Cast-Iron Hitching-Post, of which the following is a specification:

The nature of my design is fully represented in the accompanying photographic illustration, to which reference is made.

A represents a circular molded base, resting upon a flat circular plate, and above the base molding is a heavy fluted bead, on which rests the base of a tapering round column, B, having

four or more sunken panels, with Moorish arches at their upper ends. A flaring capital supports an Egyptian female head, C, with a printed and foliated helmet with drapery at the sides.

This figure I prefer to make double-faced.

What I claim as my invention is—

The design for a hitching-post, substantially as represented and described.

JOSHUA DAVIES.
